UNITED STATES PATENT OFFICE.

RUDOLPH O. TRUEB, OF MURRAY HILL, NEW JERSEY.

MANUFACTURE OF GARMENTS.

Application filed February 18, 1924. Serial No. 693,453.

My invention relates to the cutting and fitting into garments of embroidered or other ornamented fabrics; its primary object being to insure the cutting of the ornamented fabric in such a way that when the pieces are finally fitted into a garment the ornamentations on the several pieces shall accurately register in their appropriate positions in the finished article.

10 Heretofore it has been customary to place expensive ornamentation, such as bead embroidery and the like, upon piece goods, the embroidery for several portions of a single garment being disposed in separate positions 15 upon a single piece of fabric, so that the appropriate portions of the garment may be cut out from the fabric, each piece carrying its appropriate portions of the design. This cutting out has been done by the use of 20 ordinary dressmakers' patterns, which, being outlines only, cannot always be accurately positioned on the fabric so that the embroidery will be properly centered upon the cut out piece. Besides this, after the pieces 25 have been cut out, the designs are apt to be distorted from true position during the process of fitting, which involves modifications of the outlines of the piece at various points, so that when the garment is finally fitted 30 the embroidery is apt to be more or less askew. By means of which I will now explain, I am enabled to avoid these irregularities in the completed garment, and to insure the correct and accurate positioning of 35 the designs in their appropriate places in the finished article.

Fig. 1 is a view of a piece of fabric with typical ornamental designs for different portions of a dress thereon; and Fig. 2 is a view 40 of another piece of inexpensive material upon which the designs are reproduced by printing or the like and are enclosed by appropriate outlines of the several sections of the garment to which they belong.

45 The ornamented fabric 1 is usually of expensive material, such as velvet, silk, or the like, and is preferably of an appropriate size to permit the sections for a single garment to be cut therefrom.

50 Upon this fabric is placed, by the manufacturer, ornamental designs, such, for instance, as bead embroidery, indicated by the numerals 2, 3, 4, 5, 6, 7, 8, which are so placed upon the material as to leave ample 55 space around them from which the appropriate section of a garment may be cut. A try-

out pattern 9 is formed of a piece of inexpensive material, of preferably the same size as a fabric piece 1; and upon it is placed, by stamping or similar means, the pattern 60 of the embroidered ornamentation of the fabric piece 1, the various sections of ornamentation being placed in positions on the piece 9 to correspond with their positions on the piece 1, and being also surrounded by 65 the outlines of the several pieces of the garment, as 10, 11, 12, 13, 14, 15, 16, to which they relate.

When, therefore, it is desired to make up 70 into a garment the ornamented fabric, the try-out piece is first used, and the sections of the garment are cut out from it along the pattern lines. The various sections are then joined and correctly fitted on the person of the wearer of the garment, so that 75 the try-out forms a garment of the desired cut and showing the designs in the various portions of the garment in their appropriate positions. The fact that the ornamental designs are shown upon the try-out permits 80 the person, in fitting the sections, to avoid displacement of the design, as he could not do if he were working with plain unornamented pattern sections.

When the try-out has been correctly fitted, 85 it is then taken apart and the designs on the various sections are made to register with the corresponding designs on the piece goods 1. The sections are then cut from the piece 90 goods so that they correspond accurately 100 with the several sections of the try-out pattern. The fabric sections may then be united to form the finished garment, the ornamentation of the various sections centering properly, and corresponding in position 105 with the designs on the try-out pattern.

By following the above directions, the 110 purchaser of an expensive, ornamented dress pattern, for instance, is assured of being able to successfully cut out and fit the embroidered fabric, without errors, and so as to have a thoroughly artistic and well balanced finished garment, and to do this by the aid of an ordinary seamstress or garment worker, and without the aid of a highly 115 skilled tailor or artist; for my above described method eliminates the common errors of judgment which are likely to occur when an unskilled person attempts to construct a garment of expensive and highly ornamented material which is so arranged that each 120 section of the garment must be accurately

cut from a predetermined part of the material, and where mistakes in cutting cannot be remedied by cutting new pieces from another portion of the material.

- 5 It is obvious that the styles of the ornamentation for the different sections of the garment may be indefinitely varied, and that the pattern outlines can be modified to suit the different styles of garments or articles
- 10 to be made from the ornamented fabric, all without departing from the principle of my invention as described and claimed.

Having thus described my invention, what I claim and desire to secure by Letters Patent of the United States is:—

The steps in the process of cutting and fitting a garment from an expensive, woven, textile fabric having ornamental designs thereon for different parts of the garment, 20 said steps consisting in first incidentally

forming a try-out garment by cutting the parts therefor from a piece of inexpensive, woven, textile material bearing thereon copies of the designs of the more expensive material, similarly relatively positioned, 25 and also outlines of the garment parts, each outline being properly located with reference to the particular design-copy appurtenant thereto, the cutting-out of the parts being guided by such outlines, and by then assembling, modifying and fitting the parts to the person of the wearer, then separating the fitted sections thus modified, positioning them as patterns on the more expensive fabric and in proper relation to their respective designs thereon, and then cutting from such fabric the ultimate garment parts by following said pattern outlines. 30 35

RUDOLPH O. TRUER.
